UNITED STATES PATENT OFFICE.

FRANK A. SULLIVAN, OF BETHLEHEM, PENNSYLVANIA.

GAME BOARD.

Application filed September 8, 1926. Serial No. 184,253.

This invention relates to an improvement in game boards of the type usually used in playing games, such as checkers, chess and the like.

5 The object of the invention is to provide a game board of this character which affords a clear playing surface for the counters or men and yet affords pockets to receive and releasably hold the counters or men in such 10 a novel manner that even then the playing surface remains clear and unobstructed. The game board has the advantage of locking or marking unfinished games and may also be used with especial advantage in 15 problem plays.

A further object is to provide a game board having these advantages and capacities and which is of simple and durable construction easily handled, ornamental and 20 attractive, in appearance and comparatively inexpensive to manufacture.

Other objects and advantages reside in certain novel features of the construction, arrangement and combination of parts 25 which will be hereinafter more fully described and particularly pointed out in the accompanying drawings forming a part of this specification and in which—

Figure 1 is a perspective view showing a 30 game board embodying the present invention,

Figure 2 is a sectional view thereof on line 2—2 of Figure 1,

Figure 3 is a fragmentary plan view 35 thereof, and

Figure 4 is a group view in perspective of a playing piece and closure plate.

Referring to the drawings and especially to Figure 2 the numeral 1 designates generally the body of the game board. Preferably this body 1 comprises a sheet metal structure 2 in which cup-shaped pockets 3 are formed, the pockets 3 having short cylindrical body portions 4, closed bottoms 5, and open tops. The sheet metal structure 2 is embedded in a filler 6. With this arrangement the cup-shaped pockets are interconnected or integral with each other but obviously these cup-shaped pockets may be 45 made separate and embedded in the filler.

A cover plate 7 is applied to the body 1 and has a downturned marginal flange 8. The upper surface of this plate 7 is marked off in differently colored blocks or panels 55 or otherwise marked to provide the playing face of the board. The pockets 3 underlie

the blocks or markings of the playing face and in the plate 7 an opening 9 is provided for each pocket 3, the openings and pockets being alined.

60 A closure plate 10 is provided for the openings 9, each closure plate being positioned in the pocket 3 which underlies its opening 9 and having a downwardly offset flange 11 engageable with the marginal portion 12 of the opening 9 with which the closure plate 10 coacts. Thus the marginal portions 12 around the openings 9 of the cover plate constitute shoulders to limit the outward or closing movement of the closure 65 plate 10. A light coil spring 15 is provided for each closure plate 10, the coil springs being located in the pockets 3 and engaging the bottoms of the pockets and the closure plates 10. By offsetting the flanges 11 the faces 10^a of the closure plates may be and are formed to be coincident with and complementary to the outer surface of the cover plate. In this way these cover plates 70 form a part of the playing face of the board and coact with the cover plate to provide a clear and smooth playing face.

75 Playing pieces 16 such as reversible counters, men or checkers, are provided and preferably comprises body portions 17 having reduced extensions 18 at their upper and lower ends. The body portions 17 are of non-circular form preferably hexagonal and the openings 9 are of the same shape and substantially the same size so that the body portions 17 may be passed through the openings 9 when the playing pieces are properly alined therewith. The reduced extensions 18 are of circular form and smaller than the 80 openings 9.

95 With this arrangement the playing pieces 16 may be shifted across the playing face of the board in accordance with the rules of the game and all of the desirable and normal features of the conventional game board are had in that a playing face clear, smooth and unobstructed is had. However the playing pieces may be stored away in the board or locked in any position by pressing them downwardly into the pockets 3 and rotating them sufficiently to bring the corners 100 17^a thereof into engagement with the shoulders 12. Of course to enable any playing piece to be depressed into any pocket it must be alined with the pocket and its noncircular body portion must be disposed to exact registration with the opening 9 which the 105 110

closure plate 10 closes. After depressing the partial rotation effects the releasable locking and at such time the reduced portion 18 to the playing piece is coincident with the playing face of the board. A further slight rotation will bring the playing piece back into registration with the opening and permit the spring 15 to automatically reposition the playing pieces and closure plate.

10 I claim:

1. A game board comprising a body having a playing face and provided with a plurality of depressible portions, said portions being normally flush with the playing face 15 of the board and forming a part thereof.
2. A game board comprising a body having a series of pockets and also having a playing face overlying the pockets, the playing face having an opening therein over each pocket, a closure element for each pocket, yieldable means for closing each closure element, the playing face having shoulders around each pocket, and playing pieces having portions interlockable with the shoulders and receivable in said pockets.
3. A game board comprising a body having a playing face, and also having a plurality of pockets extending thereinto from the playing face, playing pieces cooperable 30 with the playing face and receivable in said pockets and cooperating means between the playing pieces and body for releasably interlocking the playing pieces and the body of the board.
- 35 4. A game board comprising a body having a playing face and also having a plurality of pockets extending thereinto, closure plates for the pockets, springs for urging the closure plates to closed position, said body having shoulders around each pocket, said closure plates having flanges engageable with the shoulders to limit the movement of the closure plates to closed position, and playing pieces cooperable with the play-

ing face and adapted to depress the closure plates, said playing pieces having portions engageable with the shoulders to hold the closure plates depressed and releasably maintain the playing pieces in the pockets.

5. A game board comprising a body having a playing face and provided with a plurality of pockets having yielding closures normally forming a part of said playing face, and playing pieces cooperable with the playing face and with the said closures. 55

6. A game board comprising a body having a series of pockets therein, a cover plate applied to the body and providing a playing face, said plate having openings overlying the pockets, the openings being of non-circular form and being smaller than the pockets and playing pieces cooperable with the playing face and corresponding in form and size to the openings the playing pieces having reduced extensions at their upper portions coincident with the playing face when the playing pieces are positioned in the pockets. 60 65

7. A game board comprising a body having a series of pockets therein, a cover plate applied to the body and providing a playing face, said plate having openings overlying the pockets, the openings being of non-circular form and being smaller than the pockets, closure plates for the pockets said closure plates having inwardly offset flanges engageable with the portions of the cover plate extending around the pockets, springs for urging the cover plates to closed position. 70 75

8. A game board having a playing face 80 and playing pieces cooperable with the playing face, said game board having pockets provided with depressible closures the pockets being adapted to receive and hold the playing pieces, and the closures to hold said 85 pieces in set position on the playing face.

FRANK A. SULLIVAN.
